UNITED STATES PATENT OFFICE.

SIMON TEPPER, OF NEW YORK, N. Y.

DESIGN FOR A SHELL FOR LIGHTING-FIXTURES.

48,163.

Specification for Design.

Patented Nov. 16, 1915.

Application filed June 26, 1915. Serial No. 36,578. Term of patent 7 years.

To all whom it may concern:

Be it known that I, SIMON TEPPER, a citizen of the United States, residing at New York city, in the county and State of New York, have invented a new and ornamental Design for a Shell for Lighting-Fixtures, of which the following is a specification, reference being had to the accompanying drawing, forming part thereof.

The figure is a perspective view of a shell

for lighting fixtures showing my new design.

I claim:

The ornamental design for a shell for lighting fixtures, as shown.

SIMON TEPPER.

Witnesses:

CLARICE FRANCK,
JUDITH PARDEE.
